PORTABLE CARTON

Crosby Field, Brooklyn, N. Y., assignor to Flakice Corporation, Brooklyn, N. Y., a corporation of Delaware

Original application April 16, 1928, Serial No. 270,257. Divided and this application September 21, 1929, Serial No. 394,180

2 Claims. (Cl. 62—87)

This invention relates to the art of preserving perishable substances and particularly to portable cartons and method of making the same.

It has hitherto been common practice to pack perishable substances such as ice cream and the like in considerable quantities in containers surrounded by a refrigerant, usually crushed ice and salt, carried within larger outer containers. It has also been common to pack smaller quantities of such perishable substances in single-chambered cartons intended to be stored in refrigerators pending final disposition. In the former case the containers have usually been relatively large, heavy and subject to leakage of the melting refrigerant, and in the latter case the cartons, once removed from the refrigerator, have failed to protect their contents from melting or other deterioration.

Among the objects of the present invention is the provision of an inexpensive light carton designed to carry both a quantity of the substance to be preserved and a quantity of refrigerant without danger of inter-mixture of the two materials and without liability of leakage of either from the carton.

A further object is to provide a method whereby such cartons may be rapidly and effectively charged with refrigerant and the refrigerant effectively sealed in place.

Such cartons, when so charged with refrigerant, may then be filled with any perishable substance with assurance that the latter will remain at low temperature for a relatively long period of time, regardless of where the carton may be kept or how it may be handled.

This application is a division of my copending application Serial No. 270,257, filed April 16, 1928, and which describes a method and mechanism for charging the cartons with a refrigerant.

One illustrative embodiment of the invention is hereinafter described and shown in the accompanying drawing wherein:

Figure 1 is a sectional view of the preferred form of carton employed, the carton being shown filled both with refrigerant and the substance to be preserved;

Figs. 2 and 3 show a mold for shaping a container for the substance to be preserved, and the manner of using the same;

Fig. 4 shows a carton inverted on a mandrel and partly filled;

Fig. 5 shows a carton inverted, filled, sealed and in a position to be removed from the mandrel; and,

Fig. 6 is a horizontal section taken on line 6—6

of Fig. 4, showing overlapping edges 42 and 43.

The carton most suitable for present purposes may be said to consist in general of an inner cup for the substance to be preserved and an outer surrounding container for holding the refrigerant. Preferably the refrigerant will not only surround the inner cup, but also will overlie one or both of its ends.

Referring to Fig. 1 which shows the preferred form of cylindrical carton C filled both with the substance to be preserved and the refrigerant all sealed and ready for delivery to the consumer, the inner cup 20 may be made up of a single sheet of fairly light paper pleated to avoid the necessity of any seam. This inner cup may be waxed or otherwise treated to render it impervious and form-retaining. The cup 20 is provided at its upper edge with a laterally extending flange 21 which is bent over and secured to the edge of an outer concentric container 22, the latter preferably being of a heavier construction. With this construction the cup 20 is completely displaced by the flange 21 from the outer container 22 by an annular space which may be filled with a refrigerant. This complete separation improves the efficiency of the carton as a means of refrigerating material in the cup 20. The outer container 22 may, for example, be made of overlapping layers of spirally wound cardboard suitably waxed or otherwise treated to make it impervious. Closing the lower end of the container 22 the circular disc 23 is sealed to and within the peripheral edge of the container 22, thus forming a closed chamber 24 to contain the refrigerant.

The substance to be preserved may be placed directly in the cup 20, but preferably it is first placed in a light seamless sack 26 also made of a single sheet of paper pleated and waxed.

This sack 26 may be filled in any suitable manner. For example, it may be placed in a mold 33 (see Figs. 2 and 3) of the same size and shape as the inner cup 20, and then filled with the substance to be preserved, the upper flared edge 27 being gathered in after filling. While obviously such mold may be of any suitable nature, a particularly useful one is shown in Figs. 2 and 3 wherein the mold is shown to comprise two complementary parts 33, 34 connected at the bottom by a hinge 35. When the sack 26 is filled to the top of the mold the latter may be spread apart to permit the easy removal of the filled sack.

Handling the filled sack is facilitated by the neck portion 27 which does not transmit heat from the hand to the contents. Further, as

shown in Fig. 1, it will form a spacing means between the sack and the container cover 28, creating a dead air insulating space, and even though no refrigerant be used at that end, the 5 carton, when packed, will still be satisfactorily heat-excluding, the cover 28 being arranged to fit tightly upon the upper end of the container 22.

From the above description it will be readily 10 understood that the inner cup 20 of the carton may be filled without difficulty by hand. If desired, the refrigerant chamber surrounding the cup 20 might also be charged by hand. Preferably, however, the introduction of the refrigerant is accomplished by machine such as described in my aforementioned co-pending application Serial No. 270,257.

Whether the refrigerant is placed in the carton by hand or by machine, it is preferable to invert it, with the cover 28 removed, and the cap 23 removed, and the cup 20 empty, onto a mandrel such as generally indicated at 40, Fig. 4. The mandrel serves to retain the desired cup shape of the cup 20 during the packing of the refrigerant in the annular space between the outer container 22 and cup 20. A mandrel, as shown in Figs. 4 and 5, is preferably of the expansible type. In the form shown in the drawing, the mandrel comprises a hollow mandrel portion 41, 30 slit from top to bottom on one side to provide overlapping edges 42 and 43 (Fig. 6), and secured to a plate 44 hingedly mounted on a table 45. For a considerable distance on both sides of the overlapping edges 42 and 43 the mandrel is cut away from, and is free of, the plate 44 so as to permit its contraction and expansion to facilitate the placement, removal and replacement of cartons. The contraction of the mandrel is effected through a toggle mechanism 46 by tipping 35 the plate 44 and mandrel portion 41 away from the table 45; the expansion being effected by tipping the plate 44 about its hinge toward table 45.

The upper end of the mandrel is protected by a cap 47 attached to the non-expansible portion. 45 When the mandrel is tipped forwardly, as shown in Fig. 5, an empty carton may be inserted thereover, and as the mandrel is tipped back into vertical position, it expands, completely filling and shaping the cup 20. This operation, while 50 providing an easy release after filling, affords protection to the more fragile cup 20 during the charging of the refrigerant.

After an empty carton has been inserted over the mandrel 41, it is preferably filled with crushed ice and salt, the two preferably being fed into the carton simultaneously but in separate streams so that the salt and ice mixture immediately surrounding the cup 20 attains a higher ratio of salt to ice than does the remainder of the 55

salt and ice mixture (see Figs. 1, 4 and 5). With this method of filling the container 22, there is provided a temperature gradient through the mixture so that a lower temperature exists at the interior of the mixture, adjacent the cup, than exists at the exterior of the mixture adjacent the container 22. Such a temperature gradient increases the efficiency of the packed carton by maintaining the coldest part of the refrigerant away from the atmosphere and immediately adjacent the substance being refrigerated.

After the carton has been filled, as shown in Fig. 5, it is sealed with a cover 23 and then removed from the mandrel 41 by tipping the carton, mandrel and plate 44 to contract the mandrel. For a more detailed explanation of the filling and sealing operation, as automatically carried out, see my aforementioned co-pending application Serial No. 270,257.

The filled carton is now inverted and the cup 20 filled with the substance to be refrigerated, supplied either in a container such as 26 or directly into the cup. The cover 28 is then put on, covering the cup 20 and re-enforcing the flange 21.

While the detailed description has herein been confined to certain illustrative embodiments it is obvious that changes may be made relative thereto without departing from the spirit of the appended claims.

I claim as my invention:

1. A carton for perishable substances comprising a cup-like inner container provided at its rim with an outwardly projecting flange, an outer surrounding container longer than said inner container, said outer container being joined at its rim to said flange at a substantial distance from the rim of the inner container to form throughout the length of the inner container an annular space to hold a refrigerant mixture of salt and ice, caps closing both ends of said outer container, and a third container fitting within the inner container to hold the perishable substance, said third container being closed at its top when filled and the top being maintained at an interval from the top cap of the carton.

2. A light portable package comprising an inner container of impervious sheet fibrous material filled with a perishable substance, an outer surrounding container of impervious sheet fibrous material forming a chamber about the sides of and beyond the end of said inner container and having its chamber charged with a refrigerant mixture of salt and ice, the greater proportion of salt being contained in that portion of the mixture disposed adjacent the inner container.
